UNITED STATES PATENT OFFICE.

WILLIAM I. CARR, OF BELLINGHAM, WASHINGTON.

AUTOMATIC DADO, EQUALIZER, AND VARIETY WOODWORKING MACHINE.

Application filed April 20, 1925. Serial No. 24,467.

To all whom it may concern:

Be it known that I, WILLIAM I. CARR, a citizen of the United States, and a resident of Bellingham, in the county of Whatcom and State of Washington, have invented a new and useful Automatic Dado, Equalizer, and Variety Woodworking Machine, of which the following is a specification.

My invention relates to improvements in automatic dado, equalizer and variety wood-working machines whereby straight and bevel cuts in all combinations are made by automatically moving cutters.

I have applied for two patents of the United States: one filed Aug. 28, 1923, Serial No. 659,718, and the other filed May 26, 1924, Serial No. 716,059, of which the present invention is an improvement. And the object of this improvement is to provide an automatic dado, equalizer and variety wood-working machine in which the saw carriages of two fully equipped and adjustable machines are driven by an electric motor on one machine by means of a shaft common to both machines and having but one universal joint therein.

I attain this object with the mechanism illustrated in the accompanying two sheets of drawings, which form a part of this specification, and in which Figure 1 is a plan view of my combined machines wherein the pivoted machine is illustrated in full lines in a diagonal position and in dotted lines in a position parallel with its companion machine and the designating characters referring to parts of the full-line drawing are the primes of the characters referring to similar parts of the dotted-line drawing, Fig. 2 is a front elevation of the combined machines showing the pivoted machine parallel with the companion machine, Fig. 3 is a side elevation of the pivoted machine, and Figs. 4 and 5 are end elevation and side elevation in section, respectively, of the sliding sprocket drawn on a larger scale.

Similar characters refer to similar parts throughout. Certain parts are broken away to show other parts hidden thereby.

More particularly: Parallel rails 4, 4 are fastened to the floor and provide a track with which grooves in base α^5 of the said

companion machine engage for reciprocal adjustment thereon. On frame 5 of the companion machine is mounted table 6, for which vertical adjustment is provided by mechanism connected to hand wheel a^6 and also for which tilting adjustment is provided by mechanism connected to hand wheel b^6 , about the center of segment c^6 .

On subbase 7 the pivoted machine is mounted. Said subbase is fastened to the floor. Frame 8 of said pivoted machine has base α^8 which is engaged with subbase 7 by pivot bolt 10 having vertical axis $x-x$. The rear end of base α^8 is arcuate about pivot axis $x-x$ and is engaged by graduated arcuate guide 11 having internal gear teeth 12. Hand wheel 13 is vertically mounted for revolution in a bearing fastened to base α^8 and has a pinion on its lower end, not shown, engaged with teeth 12. By revolving hand wheel 13 the pivoted machine is adjustable about axis $x-x$ and settable as desired by clamping screw 14 engaged in base α^8 .

Electric motor 15 is mounted on base α^8 with its shaft transversally of frame 8. On the right-hand end of said motor shaft is fastened sprocket 34. On one end of worm shaft a^{37} is fastened sprocket 36 in chain relation with sprocket 34. Silent chain 35 connects sprockets 34 and 36 for simultaneous revolution. Worm 37 is engaged with worm wheel 38 which is fastened on the front end of the shaft a^{40} of cam-slot cylinder 40. Cutter carriage 41 is reciprocable on longitudinal guides on frame 8 and is operated by arms 39 the lower ends of which are pivoted to said machine frame. The central parts of said arms mount wheels which are engaged with the cam slots of cylinder 40. Thus the revolution of said cylinder 40 causes arms 39 to vibrate. The upper ends of said arms are connected to carriage 41. Hence, motor 15 causes the reciprocation of carriage 41. Electric motor 42 is mounted on carriage 41 and has cutter 45 mounted on one end of its shaft for revolution therewith. Sprocket 19 is fastened on one end of hollow shaft b^{19} for revolution therewith, see Figs. 4 and 5. Said hollow shaft is mounted on shaft 17 with which it is

75

80

85

90

95

100

- engaged by key 20. Said key is fastened in hollow shaft b^{19} and reciprocable in key slot 18 in shaft 17. Thus sprocket 19 is caused to revolve by shaft 17 in any setting of machine 5, 6 on tracks 4—4. Sprocket wheel 22 is fastened on one end of shaft a^{23} in chain relation with sprocket 19 with which it is caused to revolve by silent chain 21. Shaft a^{23} is mounted in bearings on frame 5 for revolution transversally of said frame and parallel with rails 4. Worm 23 on shaft a^{23} is engaged with worm wheel 24. Said worm wheel is fastened to the front end of shaft 25 on which is mounted cam-slot cylinder 26. Shaft 25 is mounted for revolution in bearings longitudinally of frame 5. Arms 27, 27 are pivoted at their lower ends to frame 5 for vibration and have their upper ends connected to cutter carriage 28. 10 Wheels on the centers of said arms engage with cam slots, not shown, in cylinder 26 and the revolution of said cylinder causes said arms to vibrate and cutter carriage 28 to reciprocate. Electric motor 29 is mounted on carriage 28 with its shaft parallel with rails 4. On one end of said motor shaft is fastened cutter 30 for revolution therewith. Screw 31 is mounted for revolution in bearings 32 and 33 fastened to the floor parallel 15 with rails 4. Screw 31 is engaged with nuts a^{31} on frame 5 and is revolvable by hand wheel a^{31} .

Work stop 46 is placed on the front end of tables 6 and 9, being fastened by a pin to table 6 and by a hand clamp to table 9. The work is placed on the tables to bear against the rear side of stop 46 when the cutters shape the same. Work-holding clamp 47, which is depressed by a coil spring beneath the head of holding screw a^{47} , is fastened to table 6 and used to hold the left-hand end of the work while the operative's hand is placed on the work near its right-hand end to hold that end down and at the same time cause the work to bear evenly against stop 46.

The pivotal center of universal joint 16 is, by construction, placed vertically over the center line of pivot bolt 10, as shown clearly in Figs. 2 and 3 and also in Fig. 1 where joint 16 is broken away in part to show a portion of the upper end of said bolt 10. So that when the pivoted machine is swung on pivot 10 motor 15 revolves about the center of joint 16 and shaft 17 is not disturbed but remains parallel to rails 4. Also since sprocket 19 is revolvable by shaft 17 and reciprocable on it machine 5, 6 can be moved on rails 4 by screw 31 without interfering with the transmission of power from motor 17 to saw carriage 28. Tilting saw motor 42 in connection with pivoted machine 8, 9 provides for trimming or plowing the right-hand end of the work at a combined vertical and horizontal angle,

while provision for rectangular work only is made in machine 5, 6. This is all that the usual work done by such a combination of machines requires on one end. Although table 6 can be tilted, as described, this adjustment is not used when the two machines operate together. 70

Having thus disclosed my invention, what I claim as new and desire to secure by Letters Patent is, —

1. In machinery of the kind described in combination, a vertically pivoted machine, a transversally movable machine adjacent said pivoted machine adapted to approach and recede from said pivoted machine, a power shaft common to both of said machines, and a universal coupling in said power shaft oscillatable about the vertical axis of said pivoted machine. 80

2. In machinery of the kind described in combination, a vertically pivoted machine, a transversally movable machine adjacent said pivoted machine, a power shaft common to both of said machines, a universal coupling in said power shaft oscillatable about the vertical axis of said pivoted machine, and an electric motor on one of said machines having power connections with said shaft. 90

3. In machinery of the kind described in combination, a vertically pivoted machine, a transversally movable machine adjacent said pivoted machine, a power shaft common to both of said machines, a universal coupling in said power shaft oscillatable about the vertical axis of said pivoted machine, and power connections between said power shaft and the power mechanisms on each of said machines. 95

4. In machinery of the character described in combination, a vertically pivoted machine, a transversally movable machine adjacent said pivoted machine, a power shaft common to both of said machines, a universal coupling in said power shaft oscillatable about the vertical axis of said pivoted machine, a reciprocable cutter carriage on each of said machines, and power connections between each of said carriages and said power shaft. 105

5. In machinery of the character described in combination, a vertically pivoted machine, a transversally movable machine adjacent said pivoted machine adapted to approach and recede from said pivoted machine, a power shaft common to both of said machines, a universal coupling in said power shaft oscillatable about the vertical axis of said pivoted machine, an electric motor on said pivoted machine connected to said power shaft, and a sprocket on said transversally-movable machine mounted for revolution with said power shaft and reciprocable on said power shaft. 120

6. In machinery of the character described

in combination, a vertically pivoted machine, a transversally-movable machine adjacent said pivoted machine adapted to approach and recede from said pivoted machine, a power shaft common to both of said machines, a universal coupling in said power shaft oscillatable about the vertical

axis of said pivoted machine, and a sprocket mounted for revolution in a bearing fastened to said transversally-movable machine said sprocket also mounted on said shaft for revolution therewith and for reciprocation thereon. ¹⁰

WILLIAM I. CARR.
